UNITED STATES PATENT OFFICE.

ARTHUR J. DREW, OF PHILADELPHIA, PENNSYLVANIA.

DECORTICATING-MACHINE.

1,273,750.

Specification of Letters Patent. Patented July 23, 1918.

Application filed November 9, 1917. Serial No. 202,112.

To all whom it may concern:

Be it known that I, ARTHUR J. DREW, a citizen of the United States, residing in Philadelphia, Pennsylvania, have invented 5 certain Improvements in Decorticating-Machines, of which the following is a specification.

The machine constituting the subject of my invention is intended for acting upon 10 fibrous stalks, such as flax, either while the latter are in the natural state or after they have been subjected to the usual retting, the purpose of my invention being to effectually break up the straw or woody matter of the 15 stalk and clear the same from the fibrous strands, whereby the latter will be delivered from the machine in a properly cleaned condition free from impurities and ready for marketing.

20 In the accompanying drawings—

Figure 1 is a longitudinal sectional view of a decorticating machine constructed in accordance with my invention;

Fig. 2 is a plan or top view of the same;

25 Fig. 3 is a view on a larger scale of a part of the machine not illustrated with sufficient clearness in Figs. 1 and 2;

Fig. 4 is a transverse section on the line *a—a*, Fig. 3, and

30 Fig. 5 is a plan view, on an enlarged scale, of certain rollers constituting part of the machine.

In Figs. 1 and 2 of the drawing, 1—1 represent the opposite side frame of the machine, which have bearings for the shafts 35 of three sets of rollers *a*, *b* and *c*; two pairs of combing aprons *d* and *e*; a pair of rotary brushes *f*, and a pair of rods *g*. The first brush *f* is interposed between the first pair 40 of combing aprons *d* and the second set of rollers *b* and the second brush *f* is interposed between the second pair of combing aprons *e* and the third set of rollers *c*. The first rod *g* is interposed between the aprons 45 of the first set *d* and the second rod *g* is interposed between the aprons of the second pair *e*.

The first set of rollers *a* comprises a pair of plain rollers 2, a plurality of pairs of 50 diagonally ribbed rollers 3 and a plurality of pairs of straight ribbed rollers 4, these rollers being disposed in this order:—first a pair of plain rollers 2, then a pair of straight ribbed rollers 4, then a pair of 55 diagonally ribbed rollers 3, then another pair of straight ribbed rollers 4, then an-

other pair of diagonally ribbed rollers 3 whose ribs are at a reverse angle to those of the first pair and finally a pair of straight ribbed rollers 4. This set of rollers is at 60 the receiving end of the machine, the function of the plain rollers 2 at the beginning of the set being to crush or flatten the stalks, and the function of the ribbed rollers being to break into small pieces the straw or 65 woody fiber of the stalk which is relatively inflexible, these breaking rollers, however, having no effect upon the tough and flexible fibrous portion of the stalk, which passes between the rollers without injury.

70 By alternating straight ribbed rollers and diagonally ribbed rollers the breaking pressure upon the straw or woody fiber is exerted in different directions and the breaking of the same into small particles is more 75 thoroughly and expeditiously effected than if all of the ribs run in the same direction.

I am aware that groups of straight ribbed rollers have heretofore, in flax decorticating machines, been used in alternation with 80 groups of diagonally ribbed rollers, but I find that better results in the breaking up of the straw or woody fiber of the stalk are effected when the pairs of straight ribbed and diagonally ribbed rollers are used singly 85 and in regular alternation.

The successive pairs of rolls in the first set *a* are placed some distance apart in order that the broken particles can drop between them and thus be freed from the fibrous 90 strands.

The pairs of rollers comprising the set *a* are driven at such surface speed that there will be no tendency to subject the fibers to tensile strain in their passage from one pair 95 of rollers to the next pair of the set.

Each of the combing aprons consists of a series of transverse bars 5 (see Fig. 3) so connected together as to constitute an endless chain mounted at each end upon a supporting drum or disk 6, each of these bars being perforated for the reception of rows of teeth 7 which are carried by a bar 8 located at the back of the bar 5 and supported by means of coiled springs 9 which 100 surround pins 10, projecting from the bars 5, and are supported upon heads 11 at the inner ends of said pins, so that each bar 8, while it is normally held closely against the back of the corresponding bar 5 with its 105 teeth 7 projecting beyond the face of said bar, can be moved away from the bar 5 so as

to withdraw the points of the teeth into the openings in said bar 5. This is illustrated in Fig. 3 in which figure, however, the springs 9 and their supporting pins 10 are omitted from a number of the bars in order to prevent confusion.

The refraction of the bars 8 may be effected in any available manner at the point where it is desired to deliver the fiber from 10 the apron onto the following instrumentality of the machine. The means employed in the present instance is a cam 12 located at each side of each apron at the delivery end of the same, these cams acting upon 15 anti-friction rollers 13 mounted so as to rotate in arms 14 projecting upwardly from the bars 8 at the ends of the same.

The purpose of the aprons *d* and *e* is to comb or straighten the fibrous portions of 20 the stalks and to free the same from adhering particles of straw or woody matter, and this action will be facilitated if each apron is driven at a slightly higher surface speed than the preceding apron, or other instrumentality which feeds the fiber thereto.

The first apron of the set *d* combs the fiber from the last pair of rolls 4 and the second apron of said set combs the fiber from the first apron and prevents it from being carried down by said first apron upon the upper and lower run of the same, and in order to insure the proper hold of the teeth of the second apron upon the fibers the latter in their course from the first apron to the second are caused to pass beneath the transverse bar *g* and are thus prevented from floating along on the tops of the teeth.

When the teeth 7 are withdrawn from the fiber at the delivery end of the second apron 40 of the set *d*, said fiber can pass to the first pair of rolls of the second set *b* but in order to prevent the mass of fibers from following the course of the apron or dropping or sagging between said apron and the rollers the 45 supporting device *f* is interposed between said apron and rollers, and in order that this supporting device may also perform the additional function of helping to free the fibers from adhering particles of straw or 50 woody matter said supporting device is in the form of a brush, as shown in Fig. 3, this brush also acting upon the projecting teeth of each bar of the apron, and thus serving to free them from any adhering strands of 55 fiber or from any adhering foreign matters, whereby each bar will present clean teeth for the reception of the material from the preceding device.

The pairs of rollers comprising the second 60 set *b* are all straight ribbed rollers 4, and these have a further breaking action upon the stalks preparatory to feeding them to the combing aprons of the second set *e*, whereby a further combing of the fibrous strands is

effected preparatory to the delivery of the 65 same over the second brush *f* to the final set of rolls *c*, which comprises a preliminary pair of ribbed rolls 4 and a final pair of smooth faced rolls 2.

The rolls 4 of the set *b* interposed between 70 the aprons *d* and *e* are of lesser diameter and more closely ribbed than the ribbed rollers of the set *a*.

The first pair of ribbed rollers of the sets *b* and *c* serves to draw the fiber from the 75 brushes *f* and prevent it from being carried around by said brushes and the final pair of smooth rollers of the set *c* serves to flatten the fiber and cause it to be delivered in a sheet over the delivery board 15 in a thoroughly cleaned condition and available for spinning in case the stalks have been retted before being subjected to the action of the machine, or in condition for being degummed preparatory to spinning if the 80 stalks have been subjected to the action of the machine while in a green condition.

The various rollers and aprons of the machine are positively driven by appropriate gearing in such direction as to feed forwardly the material subjected to their action and to cause the desired acceleration in the surface speed of the successive aprons, provided such acceleration is found to be necessary in order to effect the desired 85 90 95 combing or straightening of the strands of fiber in the particular material under treatment.

By preference, the first set of rolls contains the crushing and breaking elements 100 but this is not essential to the proper carrying out of my invention, nor is it essential that a pair of toothed carrying aprons should be used between the successive sets of rolls, as a single apron may, in some 105 cases, be sufficient, although in order to obtain the best results the aprons are preferably employed in pairs, as indicated in the drawing.

I claim:

1. The combination, in a decorticating machine, of successive sets of rolls with toothed apron mechanism interposed between said successive sets of rolls and serving to receive the material from one set, convey the same 110 forward to the following set and, during such travel, to comb or clear the fibrous strands, said apron mechanism being combined with a rotary brush between the same and the succeeding set of rollers, and said 115 brush serving to support the mass of fibers in its passage from the apron mechanism to the rollers and being so located as to also clean the teeth of the successive bars of the 120 apron mechanism.

2. The combination, in a combing apron for a decorticating machine, of a series of 125 perforated bars connected to form a chain,

and each having yieldingly mounted at the back of the same a bar carrying teeth which normally project through the openings of the perforated bars and beyond the faces of the same.

3. The combination, in a combing apron for a decorticating machine, of a series of perforated bars connected to form a chain and each having at the back of the same a spring-mounted bar with teeth which pro-

ject through the perforations of the other bar and extend beyond the face of the same, and cam devices for acting upon said tooth-carrying bars and depressing the same when they reach the delivery end of the apron so as to retract the teeth to or below the surface of the perforated bar.

In testimony whereof, I have signed my name to this specification.

ARTHUR J. DREW.
